UNITED STATES PATENT OFFICE.

GEORGE LAUDER, OF PITTSBURG, PENNSYLVANIA.

BASE-PLATE FOR THE TEETH OF ORE-WASHER SHAFTS.

SPECIFICATION forming part of Letters Patent No. 299,232, dated May 27, 1884.

Application filed November 26, 1883. (No model.)

To all whom it may concern:

Be it known that I, GEORGE LAUDER, of Pittsburgh, in the county of Allegheny and State of Pennsylvania, have invented a new and useful Improvement in Base-Plates for the Teeth of Ore-Washer Shafts; and I do hereby declare the following to be a full, clear, and exact description thereof.

My invention relates to an improvement in the construction of base-plates for securing the teeth of ore-washer shafts.

I will now describe my invention, so that others skilled in the art may manufacture and use the same, by reference to the accompanying drawings, in which—

Figure 1 is an elevation of the shaft, showing the teeth and base-plate attachment. Fig. 2 is a perspective view of one of the teeth and a portion of the spiral rib of the base-plate. Fig. 3 is a transverse section of the shaft, showing the base-plate and teeth in elevation. Fig. 4 is a transverse section of a tooth and the base-plate, showing the manner of securing the teeth to the base-plate.

Like letters of reference indicate like parts wherever they occur.

Heretofore it has been customary to form the teeth of ore-washer shafts with a T-shaped base, and secure them, either with or without bolting, in a longitudinal dovetailed groove in a suitable shoe fastened to the shaft; or they have been made with a flange at the base and bolted directly to the shaft. The conveyer thus formed, however, is weak, and the blades liable to break or become detached from their fastenings. Instead of plates forming the base of the spiral, I use a series of T bars or plates, these T-bars being curved to conform to the surface of the shaft, bolted thereto, and arranged spirally thereon, with the vertical flange projecting at right angles from the base, to form a rib to which the teeth may be secured.

In the drawings, *a* represents the shaft of the conveyer, around which are secured the plates or T-bars *b*, which form the spiral. These plates *b* are of T shape, having flanges or ribs *b'* projecting vertically or at right angles from the bases. In the ribs *b'* are vertical dovetailed slots *c*, situated at suitable distances apart, for the reception of the teeth *d*. These slots *c* extend into the base-plate *b* below the surface thereof. I prefer to form the plates in sections of such a length that three of them shall make a circuit around the shaft. The

teeth *d* are plates of steel or wrought-iron of suitable thickness, with beveled edges, so as to conform to the shape of the dovetailed slots *c*. When inserted into the slots, the ends of the teeth preferably pass below the surface of the base-plate *b*, as at *g*, Fig. 4, and are firmly bolted to the projecting rib *b'* by bolts passing through the holes *f*. The plates *b*, being arranged spirally around the shaft *a*, and being securely attached thereto by bolting or in other well-known manner, form a strong and durable base or shoe for the teeth. When the conveyer is in operation, the strain on the teeth is not only in a longitudinal line, but at an angle transversely, the teeth pushing by 70 their edges and tangentially. They are, however, supported against the strain by the ribs *b'* and recessed base-plates *b*. Should any of the teeth be broken or loosened from their fastenings, other teeth are easily inserted into 75 their places.

A great advantage of my improvement is that it enables me to use flat pieces of iron or steel for the teeth without preparing them in any way, except by shearing from a sheet to 80 the proper size and shape.

If desired, I can omit either the groove *c* or recess *g*, or both.

What I claim as my invention, and desire to secure by Letters Patent, is—

1. A base-plate for ore-washer shafts, having a spirally-curved projecting flange to which the teeth may be secured, substantially as and for the purposes specified.

2. A base-plate for ore-washer shafts, having a spirally-curved vertically-slotted flange projecting at right angles from the base-plate, substantially as and for the purposes specified.

3. A base-plate for ore-washer teeth, having a flange which projects at right angles from the base-plate, said flange having a transverse tooth slot or groove at right angles to and extending into the base-plate, substantially as and for the purposes specified.

4. A base-plate for ore-washer shafts, having a spiral curve and of T form in cross-section, substantially as and for the purposes specified.

In testimony whereof I have hereunto set my hand this 21st day of November, A. D. 105 1883.

GEORGE LAUDER.
